United States Patent Office

Des. 213,238
Patented Jan. 14, 1969

213,238

BED PAN COVER

Mercedes V. Mulloy, 710½ W. 13th St.,
Eugene, Oreg. 97402

Filed Oct. 6, 1967, Ser. No. 8,888

Term of patent 14 years

U.S. Cl. D83—1
Int. Cl. D24—05

FIG. 1

FIG. 2

FIG. 3

FIG. 4

FIG. 5

FIGURE 1 is a top plan view of a bed pan cover showing my new design.

FIGURE 2 is a front elevational view of FIGURE 1.

FIGURE 3 is a side elevational view of FIGURE 1.

FIGURE 4 is a bottom view of the cover.

FIGURE 5 is a sectional, elevational view taken along line 5—5 in FIGURE 1.

The dominant features of my design reside in the portions shown in full lines.

I claim:

The ornamental design for a bed pan cover, substantially as shown and described.
